UNITED STATES PATENT OFFICE.

JOHN T. HAY, OF UNION CITY, OHIO.

BEARING-ADJUSTER.

1,154,512.

Specification of Letters Patent. Patented Sept. 21, 1915.

Application filed June 8, 1914. Serial No. 843,731.

To all whom it may concern:

Be it known that I, JOHN T. HAY, a citizen of the United States, residing at Union City, in the county of Darke and State of Ohio, have invented certain new and useful Improvements in Bearing-Adjusters, of which the following is a specification.

The object of this invention is automatically to so adjust the bearing-brasses of a cross-head pin or crank-pin of a pitman in proportion to the wear of any one or all of the brasses as to maintain a given tightness of journals at both ends of the pitman and to simplify and make more positive the mechanism heretofore used for that purpose.

The object, also, is to provide means for correcting looseness due to the spring of the metal in said automatic takeup mechanism.

I accomplish the above and other objects which will hereinafter appear, by the mechanism illustrated in the accompanying drawings, in which—

Figure 1 is a view in side elevation and partial vertical section of a pitman with my invention in operative position for adjusting the bearing-brasses at the cross-head pin and crank-pin of a pitman, the lever contact of the operative mechanism being against the cross-head pin in this illustration. Fig. 2 is a cross section on the line 2—2 of Fig. 1. Fig. 3 is a section on the line 3—3 of Fig. 2. Fig. 4 is a side elevation of a modified form wherein only one bearing lever against the pin is used, and Fig. 5 is a cross section on the line 5—5 of Fig. 4.

Like characters of reference indicate like parts throughout the several views of the drawings.

In a steam-engine, because the expansive action of the steam is exerted against both sides of the piston, that is, in alternate opposite directions, it is necessary to apply the automatic journal-box take-up at the cross-head pin of a pitman, but with internal combustion engines where the driving impulse is only against one side of the piston or in one direction, the automatic journal-box take-up may be applied at the crank-pin. In the drawings I have shown the automatic take-up mechanism as being operated by contact with the cross-head pin, as for steam-engines, but this is only by way of illustration, and it will be understood that for internal combustion engines the contact

of the automatic mechanism may be against the crank-pin at the other end of the pitman.

The cross-head pin 4 is mounted between the journal-brasses 5 and 6, and the crank-pin 7 is similarly mounted between the journal-brasses 8 and 9. The brasses 5 and 6 are mounted between the stem-members 10 of a stirrup, the outer ends of which stem-members are connected by a bar 11. The brasses 8 and 9 are mounted between the stem-members 12 of a stirrup, the outer ends of which are connected by a bar 13. The inner ends of the stem-members 12 lap the corresponding ends of the stem-members 10, and the lapped portions are united by bolts 14 thereby completing the frame or body-portion of the pitman. All of the brasses 5, 6, 8 and 9 have a close sliding fit between their adjacent pair of stem-members, 10 and 12 respectively, and it will be noted that the brasses are shorter than the diameters of the pins with which they respectively contact, so that all of the material on the sides of the brasses against the respective pins 4 and 7 will be worn away by friction against the pins.

It is not essential that the axes of the two pins 4 and 7 be maintained the same distance apart because there is room enough in the cylinder of either a steam or internal combustion engine for the stroke of the piston should the distance between the axes of said pins be somewhat increased. This permits me to adjust both of the inner brasses 6 and 9 toward their respective pins sufficiently to keep all of the brasses tight, and I will now describe the mechanism by which said brasses 6 and 9 are automatically moved toward their respective pins to take up all looseness due to wear and to maintain a predetermined tightness of said pins in their respective journals.

Mounted with a close sliding fit between the stem-members 10 is a block 15 which contacts the journal-brass 6 on one side and is provided on its opposite side with a screw-threaded socket 16 within which the correspondingly screw-threaded end of a shaft 17 is screwed. The opposite end of the shaft 17 bears against the journal-brass 9, or more frequently against shims 18 interposed between the journal-brass 9 and the end of the shaft 17.

The shaft 17 has a spline 19 extending longitudinally of one side, and mounted on the shaft 17 is a split sleeve 19, the spline of

the shaft entering the split in the sleeve to compel joint motion of rotation while permitting independent longitudinal movement between the sleeve and shaft. Mounted on the sleeve 19 is a friction-wheel 20 which rotates with the sleeve. Also, mounted loosely on the sleeve are two plates 21 which together form a pair of plates between which a pawl 22 is pivoted by a pin 23. Pivots connected with the outer end of the pawl 22 is a rod 24. The rod 24 passes through a suitable opening in the end of a bent lever 25. The opposite end of the bent lever 25 is pivoted to the lower stem-member 10 at its junction with the cross-member 11 of that yoke. The end of the rod 24 which is passed through the bent lever 25 is screw-threaded and receives a nut 26. Between the nut 26 and the adjacent end of the bent lever 25 is a spirally wound spring 27 which exerts a longitudinal pull on the rod 24 determined by the position of the nut 26 on the threaded end of said rod.

The bent lever 25 has an extension 28 in the direction of the cross-head pin 4, and this extension may be made to contact directly with the pin, but preferably it is provided with a friction-wheel 29 which makes the direct contact against pin 4.

Pivoted to the same stem-member 10 as the bent lever 25 but on the other side of the cross-head pin 4, is a bent lever 30. One end of the lever 30 is connected by a link-bar 31 with the pivot 23 of the pawl 22. The other end of the bent lever 30 terminates above the cross-head pin 4 and is provided near this end with a transverse opening through which a rod 32 passes. The end of the rod 32 which passes through the bent lever 30 is screw-threaded to receive a pair of nuts 33 and 34, which are placed on opposite sides of the end of lever 30 and the end of lever 30 between said nuts terminates with a round head to permit of a lateral movement of this end of the lever, between the two nuts, without being bound between the nuts which are screwed up to make a close fit against said rounded head. The opposite end of the rod 32 is pivoted to the bent lever 25, as shown in Fig. 1. The upper extension of the bent lever 30 is provided with a lateral extension 28 in the direction of cross-head pin 4 and this extension 28 has a friction-wheel 29 to contact with the cross-head pin 4.

Any undue looseness of the journal-brasses at either end of the pitman will permit of a longitudinal reciprocating movement of the pitman as a whole with each revolution of the crank and stroke of the piston which will impart a vibratory movement to the bent levers 25 and 30. This moves the dog 22 into position to frictionally engage the wheel 20 and rotates said wheel the fraction of a revolution thereby correspondingly

rotating the sleeve 19 and screw-shaft 17 causing the shaft 17 to screw out of its socket in block 15 against the bearing-brass 9 or shims 18, and thereby tightening the bearing-brasses at both ends of the pitman.

The reverse travel of the friction-wheel 20 during the vibrations of levers 25 and 30 which would have a tendency to loosen the journal-brasses, is prevented by a pawl 35 pivoted between a pair of plates 36, also loosely mounted on sleeve 19. The pawl 35 is held normally in locking engagement with the friction-wheel 20 by a spring 37 wrapped around a fixed bar 38 and located between the pawl 35 and an adjustable nut on the threaded-end of the bar 38.

While the two levers 25 and 30 are desirable for engines where the journal-brasses of the pitman pins are required to run loose, for close-running journals such as are most commonly used, one of said levers may be and is omitted. Preferably the lever 30 is retained because it is shorter and consequently more rigid, and because it can be applied easier and to better advantage to the pitman. Such a modification is shown in Figs. 4 and 5 wherein the extension of the lever 30' above the pivot is only sufficient to support the friction-wheel 29 against pin 4. The spring 27 around rod 24 has its inner bearing against a lug extension 42 from stem 12 of one of the stirrups. Fig. 4 also shows the use of shims 40 and 41 between the respective ends of the stirrups and their adjacent brasses to correct excessive separation of the pins 4 and 7, due to wear. The shims are inserted by hand as needed.

I have found some error in the operation of my invention in practice which I believe to be largely due to the elasticity of the metal from which the mechanism as above described is constructed, and because of this error I was unable to secure a regulated tightness of the journal-brasses until I discovered that by flattening the pin in the path of contact between it and the rollers 29 I could secure a constant limited vibration of lever 30 which had the result of correcting the error above referred to. This flattening is shown at 39 and forms the cross-head pin 4 into a cam, but this formation does not extend to those parts which contact with the journal-brasses.

While I have described my invention with more or less minuteness as regards details of construction and arrangement and as being embodied in certain precise forms, I do not desire to be limited thereto unduly or any more than is pointed out in the claims. On the contrary, I contemplate all proper changes in form, construction, and arrangement, the omission of immaterial elements and the substitution of equivalents, as circumstances may suggest or necessity render expedient.

I claim:—

1. The combination with a rotary shaft having cylindrical sides and also having a cam portion, of a pair of bearing-brasses disposed on opposite sides of the cylindrical portion of the shaft, means to move the bearing-brasses toward the shaft, and means contacting with the cam portion of the shaft for actuating said bearing-brass moving means.

2. In a journal for rotary shafts, a pair of bearing-brasses disposed upon opposite sides of the shaft, screw means to move the bearing-brasses toward the shaft, a wheel 15 through which said screw means passes, pawls making driving contact with said wheel, and means contacting with the shaft for actuating the pawls.

3. In a journal for rotary shafts, a pair 20 of bearing-brasses disposed on opposite sides of the shaft, screw means at right angles to the shaft to move the bearing-brasses toward the shaft, a wheel through which said screw means passes, pawls making driving contact with said wheel, and means comprising 25 a lever contacting with the shaft and connected with the pawls to actuate the pawls.

4. The combination in a pitman with the 30 cross-head and crank-pins, of a pair of bear-

ing-brasses for each pin disposed on opposite sides of the pin in each case, screw means extending longitudinally of the pitman to move both inner bearing-brasses toward their respective pins, a wheel through which 35 said screw passes, pawls making holding contact with said wheel, and means contacting with one of the pins for actuating the pawls.

5. The combination in a pitman with the 40 cross-head and crank-pins, of a pair of bearing-brasses for each pin disposed on opposite sides of said pins, screw means extending longitudinally of the pitman to move both inner bearing-brasses toward 45 their respective pins, a wheel through which said screw passes, pawls making holding contact with said wheel, and means comprising a lever contacting with one of said pins and connected with the pawls to actuate 50 said pawls.

In witness whereof, I have hereunto set my hand and seal at Indianapolis, Indiana, this 9th day of May, A. D. one thousand nine hundred and fourteen.
